DROPPING BOARD SCRAPER

Luty Hawkins, Mount Vernon, Ill.

Application April 20, 1940, Serial No. 330,745

8 Claims. (Cl. 15—236)

This invention relates to poultry coops and more particularly to an improved dropping board scraper for a poultry coop.

An object of this invention is to provide an improved scraper for a dropping board which is so constructed that it will scrape the board upon movement of the scraper in either direction.

Another object of this invention is to provide an improved scraper structure including a pair of scraper blades and means movable with the blades for holding the blades against the dropping board.

A further object of this invention is to provide a blade tensioning means for a dropping board scraper blade structure which is adapted to slidably engage the under side of the dropping board so as to thereby press the dropping board against the scraper blade structure, irrespective of any unevenness in the dropping board.

To the foregoing objects and to others which may hereinafter appear, the invention consists of the novel construction, combination and arrangement of parts as will be more specifically referred to and illustrated in the accompanying drawing wherein are shown embodiments of the invention, but it is to be understood that changes, variations and modifications may be resorted to which fall within the scope of the invention as claimed.

In the drawing—

Figure 1 is a perspective view of a scraper constructed according to an embodiment of this invention.

Figure 2 is a sectional view taken on the line 2—2 of Figure 1.

Figure 3 is a fragmentary sectional view of the scraper, taken on the line 3—3 of Figure 2.

Referring to the drawing, numeral 10 designates generally a dropping board which is preferably constructed of metal and is disposed in a horizontal position. An oppositely shiftable scraper structure generally designated as 11 slidably engages the dropping board 10 and is adapted to move lengthwise of the dropping board 10 in a selected direction so as to clean the upper surface of the board 10. The scraper structure 11 comprises a pair of scraper blades 12 and 14 which are disposed in upwardly convergent relation.

The blades 12 and 14 are provided at the opposite ends thereof with right angularly disposed flanges 13 and 15, respectively, which are fixed to the inner surface of a pair of vertically disposed blade supporting slide members 16 and 17. The members 16, 17 constitute a carrier for the blades

12 and 14. The supporting members 16 and 17 are constructed in substantially U-form with the bights 18 and 19, respectively. Extending at right angles and inwardly from the lower end of the bight 18 of the member 16 is a lower leg or flange 20, which engages beneath the board 10. Extending at right angles and inwardly from the lower end of the bight 19 of the member 17 is a lower leg or flange 21, which engages beneath the board 10 on the opposite side thereof from the side which the leg 20 engages beneath. The bight 18 of the member 16 is formed with a horizontally disposed inwardly extending upper leg or flange 22, which overlies the tops of the blades 12 and 14. The bight 19 of the member 17 is formed with a horizontally disposed inwardly extending upper leg or flange 25, which overlies the tops of the blades 12 and 14. The blade 12 is provided with an upper flange 23 and the blade 14 with an upper flange 24. The ends of the flanges 23, 24 engage the lower faces of the upper flanges 22, 25 of the members 16 and 17 respectively. The flanges 13 and 15 of the blades 12 and 14 are secured against the inner faces of the bights 18 and 19 respectively, by spot welding 25a or the like, whereby the blades 12 and 14 will be fixed at right angles to the members 16 and 17.

The blade member 12 at its lower edge portion is provided with an outwardly curved portion 26 and the lower terminal edge of the blade 12 is provided with a keen edge 27 adapted to slidably engage the upper surface of the board 10. The blade 14 is provided with an outwardly curved lower portion 28 and with a keen edge portion 29 engageable with the upper surface of the board 10. The blade structure hereinbefore described is adapted to be moved lengthwise of the board 10 and when the scraper blade structure is moved to the left as viewed in the drawing, the blade 12 is adapted to scrape the droppings from the board 10. When the blade structure is moved to the right, the blade 14 is adapted to scrape the upper surface of the board 10.

In order to provide a means whereby the two blades 12 and 14 may be held in sliding engagement with the upper surface of the board 10 so that in the event the board 10 is uneven, the blades 12 and 14 will nevertheless contact along their entire scraping edges with the board 10, I have provided a blade tensioning means comprising a bar generally designated as 30 which is secured as by welding 31 to the lower flanges or legs 20 and 21. The blade tensioning member 30 is formed with an arched intermediate portion 32 having the convex surface thereof slidably en-

gageable with the under surface of the board 10 and the tensioning member 30 is also formed with a pair of flat portions 33 and 34 extending from the longitudinal edges of the arched portion 31.

In practice the peak of the arched portion 32 may be slightly above the horizontal plane defined by the keen edges 27 and 29 so that the board 10 will be tensioned or slightly bent between the divergent lower edges of the two blades 12 and 14. Furthermore, the arching of the blade tensioning member 30 provides a smooth dropping board contacting surface which will permit sliding movement of the blades 12 and 14 while at the same time firmly holding the upper surface of the board 10 against the keen edges 27 and 29 of the blades 12 and 14.

The blade structure 11 is adapted to be moved lengthwise of the board 10 by means of a draft device 35 which is secured to one end of each of the slide members 16 and 17, and a second draft device 36 is secured to the opposite ends of these slide members 16 and 17. The draft device 35 is formed of a flexible member such as a wire strand which is secured at the opposite ends thereof in openings 37 and 38 formed in the bights 18 and 19, and the flexible member 35 is provided with an eye or loop 39 which is formed by twisting the central portion of the flexible member 35.

The draft member 36 is formed of a single strand of wire having the opposite ends thereof secured in openings 40 and 41 formed in the bights 18 and 19 at the ends thereof opposite from the openings 37 and 38, and a loop or eye 42 is formed in the central portion of the draft member 36.

In the use and operation of this scraper device, the dropping board 10 is inserted between the blades 12 and 14 and the blade tensioning member 30. When it is desired to scrape the upper surface of the board 10, the scraper structure 11 is moved lengthwise of the board 10 by pulling on a selected draft device, and in the movement of the scraper structure 11, the blade tensioning member 30 will yieldably and firmly hold the blades 12 and 14 in sliding engagement with the upper surface of the board 10 while at the same time, correcting any irregularities in the contour of the board 10 due to warping, bending or other circumstances.

With a scraper structure of this kind, the surface of the dropping board 10 will be thoroughly cleaned with each movement of the scraper structure 11 lengthwise of the board. In addition, in view of the fact that the slide members 16 and 17 extend considerably beyond the scraping edges of the two blades 12 and 14, these slide members 16 and 17 will form a hopper with the blades 12 and 14 so as to retain the loosened droppings in front of the blades and between the bights 18 and 19 of the slide members 16 and 17, respectively. In addition, the flanges 23 and 24 on the upper edges of the blades 12 and 14 together with the flanges 22 and 25 of the slide members 16 and 17, coact with the vertical parts 18 and 19 in forming the hopper forwardly of the scraper blades 12 and 14.

What I claim is:

1. A dropping board scraper comprising a blade structure, a pair of vertically disposed oppositely extending simultaneously shiftable end members fixed to the ends of said blade structure and extending forwardly and rearwardly therefrom to thereby form a hopper on opposite sides of said blade structure, said members depending below said structure and the dropping board, and a

blade tensioning member fixed to the lower portions of said end members and slidably engaging the lower surface of said board.

2. A dropping board scraper comprising a blade structure for travelling on the upper face of the dropping board, a pair of upright carrier members for and fixed to the opposite ends of said blade structure and being oppositely shiftable in unison, a lower flange carried by said members arranged beneath said board, and a blade tensioning member fixed on the lower surfaces of said lower flanges and slidably engaging the lower surface of the board.

3. A dropping board scraper comprising an oppositely shiftable V-shaped blade structure having the divergent edges thereof slidably engaging the upper surface of the board, a vertically disposed oppositely shiftable carrier means for and fixed to the ends of said structure, said means depending below said structure and the dropping board, and a blade tensioning means fixed relative to the lower portion of said carrier means and slidably engaging the under surface of the board to thereby hold said blade structure in contact with said board, said blade tensioning means formed of a transversely arched member disposed with the convex surface thereof slidably engaging the under surface of the board.

4. A dropping board scraper comprising a V-shaped blade structure disposed in inverted position with the divergent portion thereof slidably engaging the upper surface of the board, a pair of end members fixed to the opposite ends of said blade structure and engaging the opposite longitudinal edges of said board, a lower flange carried by each of said end members, and an elongated blade tensioning member having its ends fixed to said flanges and including a transversely arched portion slidably engaging the under surface of said board.

5. A dropping board scraper comprising a pair of scraper blades disposed in downwardly divergent relation, end flanges carried by said blades, a pair of end members fixed to said end flanges and projecting at right angles from said blades to thereby form a movable hopper, an upper inwardly projecting flange carried by said end members, a lower inwardly projecting flange carried by said end members, and an elongated blade tensioning member fixed to said lower flanges and slidably engaging the under surface of the board, said blade tensioning member including a transversely arched portion engageable with the under surface of the board to thereby hold said blades in sliding contact with the board.

6. In a combined dropping board scraper and hopper, an upstanding structure for disposing in overlapping relation with respect to and oppositely slidably relative to the dropping board, said structure including a pair of scraping blades disposed in downwardly divergent position over and for engaging said board, a pair of oppositely disposed upstanding blade carrying members fixed to the ends of and extending at right angles to the blades, said members having upper flanges overlapping the tops of the blades and lower flanges disposed below the lower face of the board, means fixed to said members and disposed on said lower flanges for maintaining the blades against the upper surface of the board, and oppositely extending traction means for said structure and secured to the ends of said members.

7. In a combined dropping board scraper and hopper, an upstanding structure for disposing in overlapping relation with respect to and oppo-

sitely slidable relative to the dropping board, said structure including a pair of scraping blades disposed in downwardly divergent position over and for engaging said board, a pair of oppositely disposed upstanding blade carrying members fixed to the ends of and extending at right angles to the blades, said members having upper flanges overlapping the tops of the blades and lower flanges disposed below the lower face of the board, means fixed to said members and disposed on said lower flanges for maintaining the blades against the upper surface of the board, and oppositely extending traction means for said structure and secured to the ends of said members, each of said blades coacting with a portion of each of said members to form a horizontal hopper open at its outer end.

8. In a combined dropping board scraper and hopper, an upstanding structure for disposing in overlapping relation with respect to and oppositely slidable relative to the dropping board, said

5 structure including a pair of scraping blades disposed in downwardly divergent position over and for engaging said board, a pair of oppositely disposed upstanding blade carrying members fixed to the ends of and extending at right angles to the blades, said members having upper flanges overlapping the tops of the blades and lower flanges disposed below the lower face of the board, means fixed to said members and disposed 10 on said lower flanges for maintaining the blades against the upper surface of the board, and oppositely extending traction means for said structure and secured to the ends of said members, each of said blades coacting with a portion of each of 15 said members to form a horizontal hopper open at its outer end, each of said blades including a flange at its upper edge coacting with the upper flanges of said members in retaining the material in said hoppers.
